COUPLING APPARATUS.

Application filed July 19, 1926. Serial No. 123,347.

This invention relates to a coupling apparatus or transformer system, and relates more particularly to a coupling apparatus especially designed for use with radio circuits 5 such as cascaded radio amplifying systems.

As is well known, it is a desideratum in certain types of selective and sensitive radio receiving apparatus and in apparatus employable near transmitting stations to construct the inductance coils of the receiving apparatus so that they are uncoupled magnetically and electrostatically to other coils and apparatus in the receiving circuit or to the transmitting apparatus. To accomplish 10 the magnetic uncoupling of the coils to other apparatus, various types of coil windings have hitherto been designed, such as double **D** windings, toroid windings and binocular coils; and to accomplish the electrostatic uncoupling of such coils to surrounding apparatus, it has been common to employ separate electrostatic shields. These prior types of 15 coil windings have, however, been found insufficient to produce the desired results on account of their relatively large external fields near the coil which produce considerable coupling to other parts and even between similar coils when placed at a moderate distance apart. To reduce the intermagnetic 20 couplings between similar coils in a radio receiving set with the use of such prior structures, it has been found necessary to so relatively arrange the coils one with respect to the other in the radio receiving set as to minimize the reacting fields. Other structural 25 difficulties, such as the large volume of winding required and the difficulty of winding methods, have also hindered the use of these prior and known types of winding coils.

40 A prime desideratum of my present invention resides in the provision of a coupling apparatus or transformer embodying an inductance coil system designed and constructed so that the external magnetic field of the 45 coil system is reduced to such a minimum that the coil system is substantially decoupled magnetically from surrounding apparatus and may be placed in close proximity to other similar coil systems of a radio receiving set 50 without intermagnetically reacting with the same.

55 A further prime desideratum of the invention resides in the provision of a coupling apparatus or transformer embodying a coil system which is self-electrostatically shielded, that is, which requires no additional or

separate electrostatic shield structure, the coil system being so designed and constructed that even when employed in a sharply tuned circuit the same will be so perfectly shielded 60 electrostatically that the hand of the operator may be brought to touch and surround the coil structure without detuning the circuit.

It is a further object of the present invention to so design and construct the inductance 65 coil system of the transformer that the mathematical and empirical conditions which satisfy the relations to produce the magnetic shielding also satisfy the relations to produce the static shielding so that the coil system is 70 both electromagnetically and electrostatically decoupled from surrounding apparatus, permitting not only the close arrangement of a plurality of transformers to produce a compactly organized radio receiving set, but permitting 75 the same to be constructed without the use of the electrostatic shielding devices.

A further principal object of my present invention comprehends the provision of a 80 variable coupling apparatus or variotransformer embodying the above-referred-to construction and one in which the coupling may be obtained over a very wide range, such for example over an inductance range of 50 to 1.

To the accomplishment of the foregoing 85 and such other objects as will hereinafter appear, my invention consists in the elements and their relation one to the other as herein-after more particularly described and sought to be defined in the claims; reference being 90 had to the accompanying drawings which show the preferred embodiment of my invention; and in which:

The figure is a cross-sectional view of the 95 coupling apparatus or transformer embodying the principles of my invention and showing the manner of connecting the same in circuit.

Referring now in detail to the drawings, 100 the coupling apparatus of my present invention comprises a secondary generally designated as **S** embodying a coil system which is self-magnetically and electrostatically shielded and a primary **P** coupled thereto, the said primary being preferably variably coupled to 105 produce a relatively large range of mutual inductance change between the primary and secondary of the transformer.

The secondary coil system of my invention 110 comprises an inner coil section **A** and an outer coil section **B** both preferably made in the form of solenoids arranged in coaxial rela-

tion, the inner coil section being wound on a drum 10 made of insulating material and the outer coil section being wound on a drum 11 made of insulating material, the said coil sections being related in the manner specified hereinafter so that the outer coil section B forms a magnetic and electrostatic shield for the inner coil section A.

The coil sections A and B are connected together at contiguous ends by the conductor 12 so that the instantaneous currents traversing the coil sections are in opposite directions, or in other words, so that opposing fluxes of different magnitudes are produced in the core 13 of the inner coil section A. Preferably as shown the outer coil joins the inner coil at the same axial end so that the two coils may be wound in the same direction. The free end 13 of the inner coil section A is the high potential end and is connected to the high potential point of the radio receiving circuit, as shown in the drawings, and the free end 14 of the outer coil section is the ground end and is connected in use to a point of ground potential in the radio receiving circuit. For reasons to be pointed out hereinafter, the outer coil preferably overlaps the inner coil and preferably so that the line joining their ends makes an angle of approximately 45° 30 with the axis of the coils, as clearly shown in Fig. 1 of the drawings.

To produce the magnetic decoupling of the coil system, I have discovered that the ratio of the turns of the two coil sections must bear a definite and quite accurate relation to the ratio of the areas of the two coils. This relation is that the product of the area and the number of turns on one coil section must be substantially equal to the product of the area and the number of turns of the other coil section. The satisfaction of this condition reduces to a minimum the magnetic coupling between the coil system and a uniform magnetic field, as well as the magnetic coupling of the coil system with other similar coils. This will be best understood when it is seen that if the coil system of my invention be placed in a uniform magnetic field of variable intensity, which field is directed for point of illustration along the axes of the coils, the E. M. F. induced in the inner coil section is equal to the E. M. F. induced in the outer coil section, since the induced E. M. F. in a coil section is a linear function of the number of turns and the total flux threading the coil. Since the product of the area and number of turns for one coil is equal to the product of the number of turns and the area for the other coil, it follows that the induced E. M. F.'s are equal. Conversely, it will therefore be seen that the resultant field at a distance is zero, since the field produced by one coil section neutralizes at a distance the field produced by the other coil section. If the field be not parallel to the axis 60 as assumed, the same conditions exists, since

the field threading the coil is to be taken as the product of the field intensity and the cosine of the angle between the coil axis and the direction of the field, this angle being the same for both coil sections.

To produce the static decoupling or shielding of the coil system, I have discovered that the coil system should be so constructed that the self-inductance of the outer coil section B be made substantially equal to the mutual inductance between the two coil sections A and B. When this condition is satisfied, there results the novel effect of no potential drop along the outer coil due to the high frequency currents flowing; so that the whole surface of the outer coil is at substantially one potential. If this potential be made the ground potential as shown in the preferred use of the coil system, it will be seen that the coil system is substantially completely electrostatically 85 shielded.

To make the self-inductance of the outer coil section B equal to the mutual inductance between the coils, I have found first that the ratio of the turns of the two coils must bear 90 the same relation to the ratio of the area of the two coils as is necessary to satisfy the requirement of producing the magnetic shielding of the coil system hereinbefore described. Thus the product of the area and 95 number of turns of one coil should be equal to the product of the area and the number of turns of the other coil. After satisfying this condition, which is the same for producing magnetic decoupling, it is generally necessary 100 only to make the length of the outer coil slightly greater than the length of the inner coil, as clearly shown in the drawings. This difference in coil length may be utilized as shown to improve the electrostatic shielding 105 of the high potential end of the inner coil, or, where this is not of primary importance, the inner and outer coils may be related symmetrically with a little overhanging of the outer coil at each end. The latter slightly 110 impairs the electrostatic shielding of the high potential end of the inner coil but slightly improves the magnetic shielding of the coil system.

When exact compliance with the last-mentioned condition is effected, I have found that it is possible to place one's hands about the outer coil without detuning, even though this coil be connected in a sharply tuned circuit as shown in the drawings.

To produce a coil system of high efficiency, I have found that the ratio of areas of the coil sections should bear a given relation. Generally the ratio of areas of the outer to the inner coil section may be between 5 to 1 and 1½ to 1, and for producing the greatest efficiency the ratio of areas should be about 2, 2.1 and 2.2 for coils having ratios of 1.26, 1.58 and 2.1 respectively, of outer coil diameter to length. These area ratios are consid- 130

- ered desirable because they give a maximum inductance for a given length of coil system having a constant outside diameter when the inner coil is wound with a constant number 5 of turns. This is a practical commercial limitation because other electrical and structural conditions impose certain limitations on coil diameters and coil lengths. The maximum number of turns per inch that can be 10 wound on the solenoid form is usually determined by the wire diameter especially at short waves where multilayer or banked windings cause a large decrease in coil efficiency. Where the area ratio of outer 15 coil to inner coil is about 2, I also obtain a high degree of static shielding with low distributed capacity in addition to obtaining maximum inductance with minimum resistance.
- 20 The results of magnetic and electrostatic shielding produced by my coil construction may also be visualized by consideration of the magnetic and electrostatic fields produced by the inter-acting coil sections. Magnetically 25 considered, the magnetic flux through the inner coil due to the current in the inner coil, which flux is the more intense flux, is slightly reduced by the opposing flux through the inner coil due to the current in the outer coil.
- 30 The inductance of the coil system arises primarily because the inner coil section has in its core a relatively intense magnetic field which is only partially neutralized by the flux of the outer coil. This partially neutralized flux within the coil has for its return 35 path the annular space between the coils. That portion of the flux of the inner coil which would tend to return outside the outer coil is neutralized by the return flux of the outer coil. It follows, therefore, that the outer coil section confines the magnetic flux and is effective as a magnetic shield.
- 40 Electrostatically considered, we may first assume that we may neglect the potential drop along the outer coil section due to the 45 resistance of the coil, since for the sharply tuned circuits in which these coils are to be used, the ratio of inductive to resistive drop is greater than 100 to 1. Now the inductive drop along the outer coil must be due to the magnetic flux linkages with this coil. Since practically the entire flux threading the coil system passes through the cone of the inner coil and back in the annular space between 50 the coils, there is no resultant flux linkage with the outer coil. This statement is to be modified only with respect to the residual flux which I have found issues radially from the center of the coil system and tends to produce neutralizing flux linkages in the halves 55 of the outer coil. Looking at the phenomenon from the viewpoint of self and mutual inductances, the inductive drop along the outer coil due to its self-inductance is neutralized by the voltage drop due to the induced 60 voltage arising from the mutual inductance of the two coils, these being equalized. Similarly the voltage drop along the inner coil is neutralized in part by the mutual between the coils, but the self-inductance of the inner 65 coil being much greater than the self-inductance of the outer coil, the fraction of inductance of the inner coil lost due to the reverse mutual is inconsequential.
- 70 The primary coil P of the transformer 75 comprises a relatively short solenoid having a diameter slightly less than that of the inner coil section A of the secondary S, so that the same may be located within the coil section A of the secondary for coupling purposes. 80 Preferably the primary P is located at the low potential end of the inner coil section A. When used in a radio frequency cascaded system, the said primary P is connected as shown to the plate circuit of an electron 85 discharge device, the transformer forming the coupling link between adjacent electron discharge devices as shown in the drawings.
- 90 In the construction exemplified in the drawings, the primary P is variably coupled to the secondary S and is preferably so coupled as to produce a mutual inductance variation over a range of about 50 to 1, the said primary P being arranged to slide in and out of the low potential end of the inner 95 coil section A by means which may comprise a supporting arm 15 pivotal about an axis O so that the primary coil may swing through an arc XYZ. The coupling variation as the coil moves from the inner position OZ to the 100 outer position OX is very rapid because of the astatic nature of the secondary combination. To secure the desired sufficiently tight coupling to the astatic system, the clearances between the primary P and the inner coil A 105 of the secondary should be reduced to a minimum.
- 110 When the coupler is constructed in this manner I have found that it produces a very desirable relation between the motion of the primary coil and the change of coupling. This relation is an approximately logarithmic one whereby a given displacement produces approximately equal percentage 115 changes of coupling at any position of the coupler between the limits OX—OZ shown. When used as a volume control in radio receivers this characteristic in the coupler produces easy and smooth control of volume for all stations both far and near.
- 120 Furthermore the coupling mechanism may be made compact and yet have a practically attainable very low minimum of coupling. Where one of the coils is astatic as shown it is not necessary to separate the coils by distances large compared with the coil diameters in order to place one coil in a region of very weak field strength due to the other coil. Furthermore the full range of coupling variation may be effected with a relatively small 125 130

movement of the movable element of the coupler.

For the preferred operation of the radio receiving system, it is highly desirable to 5 arrange the parts so that the variation of coupling does not cause any substantial variation of tuning in the coil system, and to accomplish this the primary coil P should be close only to the ground end of the secondary 10 so as to avoid building up capacitive shunts across the secondary coil system by reason of the capacity between the primary and secondary windings. The astatic nature of the secondary coils eliminates troublesome feed- 15 back couplings between a plurality of secondaries and the small size primary coil minimizes energy transfer to distant circuits by the magnetic fields due to currents flowing in the plate circuits.

20 The manner of designing and constructing the transformer of my present invention will in the main be fully apparent from the above detailed description thereof. The uses and the manifold advantages thereof, especially 25 in radio frequency circuits of the tuned and selective types, will it is thought be also manifest from the above. While I have shown and described my invention in the preferred form, it will be obvious that many 30 changes and modifications may be made in the structure disclosed without departing from the spirit of the invention, defined in the following claims.

I claim:

35 1. A coupling apparatus comprising an astatic coil system including an inner coil section and an outer coil section connected to produce opposing fluxes of different magnitudes in the core of the inner coil section, the 40 product of the number of turns and area of the inner coil section being related to the product of the number of turns and area of the outer coil section to produce neutralizing magnetic fields at a distance, and a coil cou- 45 pled to the astatic coil system, said coil being movable to and from a position within the inner coil section of the said astatic coil system.

2. A coupling apparatus comprising an 50 astatic secondary including an inner inductance coil section and an outer shielding coil section connected so that the instantaneous currents traversing the same are in opposite directions, the product of the number of 55 turns and area of the inner inductance coil section being equal to the product of the number of turns and area of the outer shielding coil section, and a primary coupled to the astatic secondary, said primary being movable to and from a position within the inner coil section of the said secondary.

3. A coupling apparatus comprising an 60 astatic coil system including an inner coil section and an outer coil section connected so 65 that the instantaneous currents traversing

the same are in opposite directions, the ratio of areas of the outer to the inner coil sections being between five to one and one and one-half to one, and the product of the number of turns and the area of the inner coil section being equal to the product of the number of turns and area of the outer coil section, and a coil coupled to the astatic coil system, said coil being movable to and from a position within the inner coil section of the 75 said astatic coil system.

4. A coupling apparatus comprising an astatic secondary including an inner coil section and an outer coil section connected to produce opposing fluxes of different magnitudes in the core of the inner coil section, the 80 self-inductance of the outer coil section being equal to the mutual inductance between the coil sections, whereby the outer coil section forms a static shield for the coil system, 85 and a primary coupled to the astatic secondary, said primary being movable from a position within and at the low potential end of the inner coil section to a position exterior thereto.

5. A coupling apparatus comprising an astatic secondary including an inner inductance coil section and an outer shielding coil section connected so that the instantaneous currents traversing the same are in opposite 95 directions, the product of the number of turns and area of the inner inductance coil section being equal to the product of the number of turns and area of the outer shielding coil section, and the length of the outer coil section being slightly greater than the length of the inner coil section whereby the outer coil section forms the static and magnetic shield for the coil system, and a primary coupled to the astatic secondary, said primary being movable from a position within and at the low potential end of the inner coil section to a position exterior thereto.

6. A coupling apparatus comprising an 100 astatic coil system including an inner coil section and an outer coil section connected to produce opposing fluxes of different magnitudes in the core of the inner coil section, the product of the number of turns and area 105 of the inner coil section being related to the product of the number of turns and area of the outer coil section to produce neutralizing magnetic fields at a distance, and a coil coupled to the astatic coil system, said coil being located within the inner coil section of the 110 said astatic coil system.

7. A coupling apparatus comprising an 115 astatic secondary including an inner coil section and an outer coil section connected to 120 produce opposing fluxes of different magnitudes in the core of the inner coil section, the outer coil section forming an electrostatic and electromagnetic shield for the secondary, and a primary coupled to the astatic sec- 130

ondary, said primary being located so as to be threaded by the flux flowing through the core of the inner coil section of the secondary.

5 8. A coupling apparatus comprising an astatic secondary including an inner inductance coil section and an outer shielding coil section connected so that the instantaneous currents traversing the same are in opposite

directions, and a primary coupled to the astatic secondary, said primary being located so as to be threaded by the flux flowing through the core of the inner coil section of the secondary. ¹⁰

Signed at New York city, in the county of ¹⁵ New York and State of New York, this 16th day of July, A. D. 1926.

LESTER L. JONES.
